UNITED STATES PATENT OFFICE

116,063

DESIGN FOR A LIGHTING FIXTURE OR SIMILAR ARTICLE

Lemuel L. Stewart, Elkhart, Ind., assignor to
The Adlake Company, a corporation of Illinois

Application November 24, 1937, Serial No. 73,179

Term of patent 14 years

To all whom it may concern:

Be it known that I, Lemuel L. Stewart, a citizen of the United States of America and a resident of Elkhart, county of Elkhart, and State of Indiana, have invented a new, original, and ornamental Design for a Lighting Fixture or Similar Article, of which the following is a specification, reference being had to the accompanying drawing, forming a part thereof, wherein

Fig. 1 is a front elevational view of a lighting fixture or similar article showing my new design;

Fig. 2 is a bottom plan view;

Fig. 3 is a sectional view taken on the line 3—3 of Fig. 2.

The design is characterized by a converging

lens of the configuration shown, which is thicker at its center than at its edges, having a spheroidal exterior surface and having a diameter approximately three times its thickness at the center combined with a plain, unbeaded flange projecting radially outwardly from its upper portion, said flange having a diameter greater than that of the lens, so that the entire outer edge of the flange is visible from a point directly below the fixture.

I claim:

The ornamental design for a lighting fixture or similar article, substantially as shown and described.

LEMUEL L. STEWART.
